UNITED STATES PATENT OFFICE.

WILLIAM CONNER AND CHARLES W. MITCHELL, OF WILMINGTON, DEL.

IMPROVEMENT IN FLOOR-CLAMPS.

Specification forming part of Letters Patent No. 71,987, dated December 10, 1867.

To all whom it may concern:

Be it known that we, WILLIAM CONNER and CHARLES W. MITCHELL, of the city of Wilmington, in the county of New Castle and State of Delaware, have invented a new and Improved Clamp for Clamping Ship-Timbers, Flooring, and other Carpenters' Work; and we do hereby declare that the following is a full, clear, and exact description of the construction and operation of the same, reference being had to the annexed drawings, making a part of this specification, in which—

Figure 1 is a perspective view; Fig. 2, a front view.

a is the frame; *b*, the screw used for forcing the work in its place; *c*, the bed for the working of the screws; *d d*, screws for moving the wedges and holding them in place when the clamp is set; *e e*, blocks for the sliding of the wedges; and *f f* are the wedges, playing or sliding in these blocks by means of the dovetailed ways or grooves *g g* and tongues *h h*. *i i* are plates for holding up to their places, by means of the screws *d d*, these wedges and blocks.

To enable others to make and use our invention, we will proceed to describe its construction and operation.

We construct our clamp of iron, providing a frame, *a*, with a stationary bed-block, *c*, for working the clamping-screw *b* obliquely through it. Under this frame, and suspended to it by means of the screws *d d* and the sup-

porting sliding plates *i i*, we set the grooved blocks *e e*, in which the dovetailed tongued wedges *f f* play. These blocks and wedges are moved, by means of the plates and screws, to the required distance or width of the timber to which it is to be fastened, and when set to its place for working, the wedges, playing in the blocks, tighten and hold the clamp to its place.

In operating this clamp we adjust it to the joist or timber by means of the above-described blocks and wedges, and their set-screws and plates, and then drive home the plank, board, or timber to the desired place by operating with the clamp-screw *b*.

We do not claim the screws or wedges in themselves, as we are well aware that screws and wedges have been and are used in clamps; but

What we claim as our invention, and desire to secure by Letters Patent, is—

The combination of the frame *a*, with the screws *b* and *d d*, with the wedge-blocks *e e*, wedges *f f*, and plates *i i*, constructed and arranged, as herein described, to operate as a clamp for clamping ship-timber, flooring, and other carpenters' work.

WM. CONNER.
CHARLES W. MITCHELL.
